CHECK WRITER

Joseph Leroux, Toledo, Ohio, assignor to The
Leroux Sales Company, Toledo, Ohio, a corpora-
tion of Ohio

Application June 10, 1946, Serial No. 675,773

2 Claims. (Cl. 101—20)

1

This invention relates to contributing to the maintenance of an elected marking on sheet material.

This invention has utility as a marker of the check writer type. Type characters or numbers are selected from independent supply ways, accumulated in the desired sequence and thrust past an inking station to a position over the instrument to be marked against alteration. At this position a scarifying impress of the entire grouping of the characters is effected in a single operation upon the check.

Referring to the drawings:

Fig. 1 is a plan view, with parts broken away, showing an embodiment of the invention in a compact check writer;

Fig. 2 is a section on the line II—II, Fig. 1, showing, with characters omitted features of the scarifier and inking means for the writer;

Fig. 3 is an end elevation from the right of Fig. 1, showing a character in the trunk way, and a slide door, openable to permit character supply or removal;

Fig. 4 is a perspective view on an enlarged scale of a type or character; and

Fig. 5 shows a fragment of a negotiable instrument bearing the scarified printing marking thereon.

Upon pads or suction feet 1 there may be mounted a general frame unit 2, preferably of metal or plastic, sufficiently substantial to maintain service in normal office operations. From an end 3 of the unit 2, there extends a trunk way 4 having a reduced width top slot-providing portion 5.

Perpendicular to the way 4, are branch ways 6 having reduced width top slot portions 7 extending to the slot 5, as feeder ways thereto and receiving branches therefrom.

At an opening 8 in the bottom of the way 4, and protruding upwardly into the way 4, is an inking roller 9, say of soft fibrous material. An ink supply pocket or reservoir 10 has a retainer plate 11, shiftable to allow resupply of marking substance.

A crank 12 is at the opposite or back side 13 of the frame 2. The crank 12 is normally down against a pin or stop 14 protruding from the side 13. The crank 12 is fixed on a shaft 15 extending transversely thru the frame 2 to a front side 16. A top 17 for the frame 2 has therein the slot 5 and its branches 7. An opening 18 downward from the way 4 in the region beyond the inking roller 9 away from the branch ways 6, has the shaft 15 extend thereacross. Keyed to the shaft 15 in the opening 18 is an eccentric or

2

cam 19 in a frame 20. Rocking of the shaft 15 moves the eccentric 19 and thereby thru the frame 20 lifts a scarifier bar 21 having its parallel marking ribs 22 as a continuation of the way 4 bottom portion.

End 23 of the frame 2, remote from the end 3, and extending down from the top 17 between the sides 13, 16, has an opening or slot 24 into which may be introduced an end 25 of a blank check 26. For locating amount writing region 27 of the check 26 at the region to ride under the slot 5 and over the marker platen 21, guide pins 28 may be adjusted, while adjustable stops 29 at an opening or window 30 may determine the push-in limit for the end 25 of the instrument 26.

The issuer of the check may desire a special notation 31, the normal location for which may be, after having been thrust over the inking roller 9 in the passage of the notation 31 along the way 4 and protruding thru the slot 5 to arrive at the portion of the slot 5 near the end 23. However, before issuing a check, the operator should shove the character 31 over the inking roller 9 in the event re-inking be required, and then return the character 31 to the location shown.

At the end 3 of the frame 2 is a slide door 32, which, as opened, permits the introduction of a special character 31, as well as the normal notation units. A type element 33 carries a readily visible notation disclosing face 34 opposite from its printing face 35. Between these faces, the element 33 has parallel opposite guide way grooves 36, complementally coacting in a way 7. Check notation 37 at the ends of the respective ways 7 on the top 17 allow the operator to verify the alley or branch 7 to which return of the character as removed may be taken, as well as initially stocking the check writer with its printing characters. In the plane of the grooves 36, 40 is a pair of parallel shoulders 38 for cooperation along the way or slot 5 as the type element be removed from its reserve branch in selection for use. For this operation, the characters are taken in the order sought for the total, reading from the left. Observing this order in taking the respective type from the branches to the way 4 to move along its slot 5, the characters in this transit toward the region for printing at the platen 21, pass over the inking roller 9. This movement causes the compressible face of the roller 9 to engage frictionally sufficiently with the type in this transit to bring up ink for a succeeding type element following this course. The loosely located roller 9 at the opening 8 above the ink well or reservoir 10, has a slight slippage as to the type

sufficient to wipe some ink upon the printing face 35.

With the selected notations grouped compactly together in the slot 5 of the way 4 over the platen 21, the check 26 to be marked, is thrust thru the opening 24 for its to-be-marked region 27 to register under the type in the way 4. The crank 12 is then grasped and swung upward away from the stop 14. This causes the cam 19 to ride against the underside of the platen 21, and squeeze its cutting ribs 22 into the back side of the check 26 in the movement of the platen 21 against the characters on the faces 35 as aligned for the elements 33. Scarified marking 39 is thus made on the check 26.

What is claimed and it is desired to secure by Letters Patent is:

1. A marking tool comprising a frame having a seat for an object to be marked, a slide way in the frame for type character elements, said way extending to and across a portion of said seat, a plurality of branch ways independently extending to said slide way at a portion of said way remote from said seat, character elements adapted to be selectively shifted from the respective branch ways directly to the slide way in a desired sequence therefor for movement along the slide way to the seat in forming an assembled lineal extent group, an object scarifying independent platen unit of continuity for the lineal extent of and at the opposite side of the object from the group at said way, there being guide means in the frame for an object to be marked to be positioned between the scarifying platen unit and the group of character elements, and shifting means for the platen unit relatively to the frame held group at the way for effecting group controlled scarifying marking of the object.

2. A marking tool comprising a frame having a seat for an object to be marked, a multi-section way in the frame for type character elements, a plurality of branch ways independently extend-

ing to a first section of said slide way, second and third slide way sections, said second section of said way providing inking means spacing the first section from the third section extending to and across a portion of said seat, character elements adapted to be selectively shifted from the respective branch ways directly into said first section in a desired sequence in passing therefrom and thru the second section, to be there inked, into the third section in a lineal extent group, an object scarifying independent platen unit of continuity for the lineal extent of and at the opposite side of the object from the group at said way third section, there being guide means in the frame for an object to be marked to be positioned between the scarifying platen unit and the group of character elements, and shifting means for the platen unit relatively to the frame held group at the way for effecting group controlled scarifying marking of the object.
